UNITED STATES PATENT OFFICE.

GEORGE B. KAISER, OF CINCINNATI, OHIO.

TAILOR'S MEASURING DEVICE.

SPECIFICATION forming part of Letters Patent No. 794,506, dated July 11, 1905.

Application filed May 15, 1905. Serial No. 260,365.

To all whom it may concern:

Be it known that I, GEORGE B. KAISER, a citizen of the United States of America, and a resident of Cincinnati, county of Hamilton, 5 State of Ohio, have invented certain new and useful Improvements in Tailors' Measuring Devices, of which the following is a specification.

The object of my invention is a device which 10 provides a tailor with an accurate means of measuring the curvature of the spinal column, the position of the neck, the height of each shoulder, and the contour of each hip to enable him to secure an accurate fit of a garment. 15 This object is attained by the means described in the specification and illustrated in the accompanying drawings, wherein—

Figure 1 is a rear elevation of a measuring device embodying my invention, a part of the 20 vertical main rod being broken away and the severed parts being brought together to economize space. Fig. 2 is a side elevation of the same, the parts being broken away as in Fig. 1. Fig. 3 is a detail view of the neck portion. Fig. 4 is a horizontal sectional view on line 25 4 4 of Fig. 2. Fig. 5 is a similar view upon line 5 5 of Fig. 2. Fig. 6 is a similar view on line 6 6 of Fig. 2, and Fig. 7 is a sectional view upon line 7 7 of Fig. 1.

Referring to the parts, the main vertical rod A has a longitudinal rib *a* running its entire length. At the lower end of the rod A is an adjustable slide *a'*, which carries an inwardly-projecting arm *a''*, which is to be adjusted to fit between the limbs of the person being measured, so as to cause the vertical rod to be positioned over the spine. Above the slide *a'* is positioned a slide B, which consists of a member *b*, a plate *b'*, and a channel-iron 35 *b''*. The member *b* has a recess *b''* to fit over the front face of the rod A and has perforations *b'''* *b''''* to receive screws which pass into plate *b'*, which fits against the rear face of the rod A. Channel-iron *b''* is pivoted upon a pivot 40 *b''''*, which projects from plate *b'*, so that the channel-iron may take either a vertical or a horizontal position. Channel-iron *b''* forms a way in which the hip-measuring arms C C' slide. These arms C C' at their inner ends 45 are tapered down, so that they may pass each

other within the channel-iron. Each of the arms C C' has longitudinal slots *c* *c'* to pass the shank of screws *c''* *c'''*, which are secured in the ends of the channel-iron to enable the arms C C' to be distended or retracted independently to any position desired. Arms C 55 C' have pivoted to their outer ends arms *c''* *c'''*, which are adapted to fit against the sides of the hips of the person being measured.

Above the sliding member B upon the rod 60 A is a secondary slide D, which consists of a member *d*, recessed to fit over the rib *a* and front face of the rod A and perforated to pass screws *d''* *d'''* to engage the secondary member *d''* of the slide. Upon screws *d''* *d'''* are 65 pivoted arms *d''''* *d'''''*, which are adapted to abut against the shoulder-blades. To the upper end of rod A a short rod E is pivoted, which has a rib *e*, similar to rib *a*, and is pivoted to rod A at the point *e'*. Rod E has secured to its lower 70 end a worm *e''*, which passes down through an internally-screw-threaded nut F, which is seated in a recess *a''* at the upper end of rod A. By turning nut F the rod E may be made to assume different angles to the rod A, the amount 75 of the angle being measured by finger *a''''*, secured to the upper end of the rod A, and a circular scale marked upon the rod E. Rod E is perforated at *e''''* to receive a pin *e'''*, upon which a graduated disk G is secured against the rod 80 E. Upon the end of pin *e'''* arms H H' are independently pivoted. Arms H H' carry at their outer ends inwardly-projecting arms *h* *h'*, which may be brought to bear upon the shoulders of the person being measured. The 85 graduations upon the disk G indicate the respective angles of the shoulders when the arms H H' are adjusted to contact the same. At the upper end of rod E a metal bracket K is pivoted at *k*. Bracket K straddles the upper 90 end of the rod E and projects above the same to form a way *k'*, in which the graduated sliding arm *k''* is located. The arm *k''* carries at its inner end a collar *k''''*, which is to be brought against the neck of the person being measured 95 at the point where it is desired to have the coat-collar come. The bracket K has perforations *k'''* to receive a set-screw *k''''* for clamping the sliding rod *k''* in position.

In use it is seen that by adjusting arm *a''* 100

between the limbs and the collar k^3 at the neck of the person being measured the vertical rod A is located over the spine. The independent adjustment of the arms C C' gives 5 the relative sizes of the hips. Then the arms d^4 d^5 being made to bear against the shoulder-blades by the manipulation of the screw F, the arm E may be made to take an angle relative to the arm A such that the position of 10 the person is indicated—that is, whether or not he is stooped, normal, or over-erect. Then the arms H H' may be independently operated to get the relative slopes of the shoulders. The arm k^2 gives the position of 15 the neck.

What I claim is—

1. In a tailor's measuring device the combination of a main rod, means for adjusting it over the spine, a secondary rod pivoted at 20 the upper end of the main rod, means for varying and for measuring the relative angles of the two rods to each other, and a neck-measuring device carried at the upper end of the secondary rod.
2. In a tailor's measuring device the combination of a main rod, means for adjusting it over the spine, a secondary rod pivoted at the upper end of the main rod, means for varying and for measuring the relative angles 25 of the two rods to each other, a graduated disk secured to the secondary rod and independent shoulder-measuring arms pivoted to the rod at the disk.

3. In a tailor's measuring device the combination of a main rod, an inwardly-projecting rod at its lowermost end for centering the main rod over the spine, a sliding member upon the main rod and having ways formed therein for hip-measuring arms, independent hip-measuring arms sliding in the ways in 40 said sliding member, a secondary sliding member carrying arms to bear against the shoulder-blades, a secondary rod pivoted at the upper end of the main rod, a graduated disk carried by the secondary rod, shoulder-measuring arms pivoted to the secondary rod and disk, means for varying the relative angles 45 of the main or secondary rods and a neck-measuring rod carried by the secondary rod.

4. In a tailor's measuring device the combination of a main rod, means for adjusting the same over the spine of the person being measured, a secondary rod pivoted at the upper end of the main rod, a bracket pivoted to the upper end of the secondary rod and having a way formed therein, an inwardly-projecting graduated rod carried by the bracket, a collar-piece carried by the graduated arm, and means for changing the relative angles 55 of the secondary and the main rod and of the secondary rod and its bracket.

GEORGE B. KAISER.
